SPINAL CORD TREATING APPARATUS

Susumu Koizumi, 27-8 Kidacho, Neyagawa,
Osaka, Japan

Filed June 8, 1970, Ser. No. 23,343

Term of patent 14 years

Int. Cl. D24—02

U.S. Cl. D83—1

FIG. 1

FIG. 2

FIG. 3

FIG.4

FIG.5

FIG.6

FIG.7

FIG. 1 is a plan view of the spinal cord treating apparatus, as shown and described.

FIG. 2 is a front elevation view thereof;

FIG. 3 is a bottom view thereof;

FIG. 4 is a rear elevation view thereof;

FIG. 5 is a left elevation view thereof;

FIG. 6 is a right elevation view thereof; and

FIG. 7 is a section on the line 7—7 in FIG. 1.

I claim:

The ornamental design for a spinal cord treating apparatus, as shown and described.
